UNITED STATES PATENT OFFICE.

JOSEPH J. ATKINSON, OF HOUSTON, TEXAS.

FILING-CABINET.

No. 920,243.

Specification of Letters Patent.

Patented May 4, 1909.

Application filed November 28, 1908. Serial No. 464,922.

To all whom it may concern:

Be it known that I, JOSEPH J. ATKINSON, a citizen of the United States, residing at Houston, in the county of Harris and State 5 of Texas, have invented a new and useful Filing-Cabinet, of which the following is a specification.

My invention relates to cabinets or cases for filing letters, memoranda, accounts or 10 other analogous matters, and the object of my invention is to provide a case or cabinet which may be used to form a unit with other cabinets for the production of a complete filing case of any desired size.

15 A further object of my invention is to provide a case in which the division plates dividing the classified materials may be easily turned downward to permit the matter contained between the division plates or cards 20 to be quickly and easily gotten at or withdrawn. In this connection I also provide means whereby the division plates or cards may be supported in position and held snugly against the contents of the case so as 25 to hold the division plates in a vertical position, while, at the same time, these holding means may be easily removed and placed at any portion of the case to allow for the expansion of the material contained within the 30 cabinet.

Other details of my invention relate to the construction of the cabinet and have for its object the simplifying of this class of devices.

35 I have shown two embodiments of my invention in the drawings, wherein,

Figure 1 is a perspective view of one form; Fig. 2 is a longitudinal vertical section thereof, particularly showing the means of 40 attaching the alining cord; Fig. 3 is a perspective view of another form of box or tray; Fig. 4 is a transverse section thereof; and Fig. 5 is an enlarged detail fragmentary section.

45 Referring to the drawings, 2 denotes a box of any suitable size or shape, but preferably rectangular and longitudinally extended, the material of the box being adapted to hold therein a series of main division plates 50 or cards, 3, and a series of minor division plates or cards, 4. There may be as many separate plates or divisions, both major and minor, as desired, to accommodate the device to any particular business or object.

55 Passing through the rear lower corner of the box is the alining rod, 5, of any desired ma-

terial and supported at its ends in bracket pieces attached in any desired manner to the ends of the box. The division plates 3 and separating cards 4 are perforated at their rear lower corners for the passage of the rod 5. Of course, it is to be understood that the farther back the rod 5 is placed, the better, inasmuch as the papers or memoranda to be filed are to be placed between the minor 60 division plates 4, and therefore there should be as much room as possible.

In vertical line with the rod 5 is the slack cord or other flexible connection, 6, attached at its ends to the ends of the box 2 in 70 any desired manner and passing through perforations in the rear upper corners of the division plates 3 and through the rear ends of the minor division cards 4. This cord is of considerable importance as its slackness 75 permits the division plates or cards to be turned over upon their sides at an angle as shown in Fig. 1, thus permitting the easy removal of memoranda or other matter contained between any particular two division 80 plates. It will be seen that a rigid rod arranged longitudinally to the box at the height of the cord, 6, would necessitate that the division cards and plates be slotted. This tends to weaken the cards and even 85 then does not permit the degree of flexibility attained by the use of the flexible cord 6.

In order to hold the cards 3 and 4 in their upright position and to hold the papers contained between the cards in a compacted 90 form, I provide the removable pins, 7 and 8, which may be placed respectively in any one of the series of holes, 9 and 10, arranged in the back and bottom of the box. In Fig. 3 the cards are shown as being held in their 95 upright and compact form by means of the pins 7 and 8, while in Fig. 1 the pins are removed to show the cards arranged at an inclination to permit withdrawal of matter.

In order to fasten the cord, 6, snugly in 100 place I preferably form an opening, 11, in each end of the box through which the ends of the cords 6 are passed and knotted. A plate 12 of metal having a hole which is smaller than the knot 13 of the cord 6 is then 105 attached to the inside of the end of the box. This prevents the withdrawal of the cord from the inside. The hole 11 is preferably filled up in any desired manner, as by a filling 14 of wood, putty, or other suitable material. 110 While I have found in practice that this manner of attaching the cord to the box

ends is thoroughly effective and simple, I do not wish to be limited thereto, as the cord might be attached in any manner desired.

In Fig. 3 I show a modified form of cabinet or case in which the upper portion of the case or box is removed and the sides are downwardly and forwardly inclined so as to permit the more ready handling of the compacted cards and division plates. Otherwise than this that the box is in the form of an open-top tray having diagonally-edged ends, there is no difference between the construction in Fig. 3 and that in Fig. 1. Preferably in the use of my device I use three separate sizes of division plates or cards, namely, the larger cards 3, which are lower in height than the remainder of the cards, but project out farther and form the major division of the contents, the cards 4 which are shorter than the cards 3, but which are higher, and the intermediate cards 15 shown particularly clearly in Fig. 4. These intermediate cards are smaller than the cards 4, permit the finger to be very readily inserted between the cards 4 to separate the same, and thereby permit the ready handling of the cards to separate the same and get at the contents thereof.

Fig. 5 shows a detail of the pins 7 and 8. It will be seen that the pin is preferably formed with a shank provided with a shouldered portion 16 to prevent the insertion of the pin too far into the hole 9 or 10, and a head, 17, permitting the ready withdrawal or handling of the pin.

While I have shown my construction as using cards forming division plates or septums, I do not wish to be limited to this, as of course, the cards themselves might be used to contain memoranda and be inserted into place in the manner usual in card systems wherein the cards cannot be withdrawn except by the withdrawal of one of the alining rods. To this end the rod 5 might be provided with means whereby it could be easily withdrawn from the box and from engagement with the cards. In the construction shown this might be very easily detached by unscrewing the screws, 18, in the end of the box whereby the rod 5 may be withdrawn. The connecting cord 6 also may be withdrawn by removing the plates 12. My intention, however, is to have these boxes made with a sufficiency of dividing septums or cards so that there shall be no need of withdrawal or change in these cards, but that letters, clippings, memoranda, etc., may be filed between the cards which are properly indexed by number, letter, etc., to that end.

The box form of my filing cabinet which is shown in Figs. 1 and 2 is very well adapted to be used as a unit and built one on top of the other as shown in dotted lines in Fig. 2, to form a complete filing case and these

units are of a size adapting them to be conveniently removed from the complete set of boxes or files to the desk. The tray form, however, shown in Figs. 3 and 4 is most convenient for use upon the desk to contain documents or unfinished correspondence and like matters.

While I have shown what I deem to be the preferred form of my invention, it is to be understood that I may vary it in many ways without departing from the spirit of my invention and that I have illustrated my invention in the drawings in its simplest terms. My construction might be made of very ornamental nature while yet preserving the simplicity which adapts it to the exigencies of business.

From the foregoing, it is thought that the construction, operation and many advantages of the herein described invention will be apparent to those skilled in the art without departing from the spirit or sacrificing any of the advantages of this invention.

Having thus described my invention, what I claim as new and desire to secure by Letters-Patent, is:

1. A cabinet having a bottom and two side pieces, a series of cards within the cabinet, and a flexible slack connection attached at its ends to the ends of the cabinet and passing through the cards.

2. A filing cabinet including a bottom and two end portions, a rigid rod adjacent to the bottom of the cabinet and extending between its ends, septums arranged within the cabinet through which said rod passes, and a flexible slack connection attached at its ends to the ends of the cabinet and passing through the upper portion of said cards.

3. A filing cabinet including a bottom and two ends, a rigid rod extending between said ends adjacent to the bottom of the cabinet, and a flexible slack connection above the rod and attached at its ends to the end pieces of the cabinet, both rod and flexible connection being adapted to pass through a series of filing cards.

4. A filing cabinet consisting of a bottom, two end pieces and a rear piece, a construction adapted to pass through a series of septums, the bottom and rear of said cabinet being provided with a series of perforations, and pins adapted to be inserted in said perforations and to contact with the front and rear of the cards to hold the same in place.

5. A cabinet comprising a bottom, a rear piece and two end pieces, a flexible connection between the two end pieces adapted to pass through a series of septums, and pins adapted to be inserted in a series of perforations in the back piece and bottom for the purpose of holding the lower and rear edges of said cards.

6. A filing cabinet comprising a bottom, a back piece and two end pieces, a transverse

rod arranged between said end pieces adjacent to the junction of the rear piece and bottom of the case, a flexible slack connection between the end pieces located above said rigid rod, a series of septums having perforations through which said flexible connection and rigid rod pass, and pins adapted to hold the lower and rear edges of the cards fastened, said pins passing through a series of 10 perforations in the bottom and rear end the case.

7. In a filing cabinet, the combination with a case having a bottom, a rear and two end pieces, said bottom and rear pieces being provided with a series of perforations there- 15 through, a rigid rod extending between the end pieces near the bottom of the case, a flexible slack cord attached to the end piece

above said rigid rod, and pegs for insertion into said series of holes, of a series of septums 20 adapted to be inserted within said case, said cards having upper and lower perforations on their margins to receive the rigid rod and the flexible cord, said cards being divided into sections by dividing plates less in height 25 than the cards but extending out beyond the same, some of said cards being smaller than the others, both in height and depth.

In testimony, that I claim the foregoing as my own, I have hereto affixed my signature 30 in the presence of two witnesses.

JOSEPH J. ATKINSON.
